HIGH-FREQUENCY TUBE STRUCTURE

John R. Woodyard, Garden City, N. Y., assignor
to The Sperry Corporation, a corporation of
Delaware

Application August 20, 1945, Serial No. 611,636

9 Claims. (Cl. 315—5)

1

The present invention relates to high frequency apparatus, and more particularly to high frequency electron discharge tube apparatus of the velocity modulation type using cavity resonators.

Known means for and methods of tuning and/or frequency modulating electron discharge tube devices of the velocity modulation type having one or more cavity resonators suffer from one or the other, sometimes both, of the following defects. In the first place, electrical tuning by conventional methods, such as by varying the electron beam voltage, or by changing the reflector electrode voltage (in electron discharge tubes of the reflex type), yield only a small amount of frequency shift, usually of the order of magnitude of one percent or less. If attempt is made to increase the electrical tuning range by altering the tube design, the efficiency of operation is considerably reduced because the known methods of electrical tuning are not actually tuning at all, but, rather are merely methods of forcing the cavity resonator to oscillate off its natural frequency. These methods cannot change the frequency by more than approximately $1/Q$.

Secondly, methods of varying the frequency of such velocity modulation electron tube devices which force the cavity resonator to oscillate appreciably off its natural frequency, also suffer the disadvantage that these methods vary the amplitude as well as the frequency of the electromagnetic energy output, since the resonator is then operating down from the peak of its resonance curve as soon as the frequency departs from the resonant frequency. These defects can be overcome substantially only by changing the natural frequency of the cavity resonator.

Certain known types of mechanical tuning, as by deforming the resonator dimensions and/or shape or by inserting and moving conducting bodies within the resonator, do change the natural frequency of the resonator and, therefore, furnish a relatively large tuning range free from amplitude modulation. However, mechanical tuning, in general, suffers from the disadvantage that it is not readily applicable for use in frequency modulation, especially when the modulation signal voltage is of very high frequencies, such as are encountered in television or related arts. Such tuning is also awkward to use in automatic frequency control systems. The inapplicability of mechanical tuning is, to a large extent, due to the inertia of the moving parts.

It has been shown by J. P. Blewett and S. Ramo, in the Journal of Applied Physics, 1941, that an electron cloud or space charge which is caused to

2

rotate about an axis of gyration by the action of magnetic and electric fields is characterized by a variable dielectric constant, the magnitude of which depends on the angular velocity of rotation of the cloud and, hence on the magnitude of the forces involved in producing the rotation of the electron cloud. If the electron cloud rotation is produced by a magnetic field oriented at right angles to an electric field and to the direction of electron emission, the variation of the dielectric constant of the space occupied by the rotating cloud is dependent on the strengths of the magnetic and electric fields. The dielectric constant thus obtainable is less than that of free space and may have values ranging from unity to zero or even negative values.

In accordance with the present invention, it is proposed to provide, in the cavity resonator of electron discharge devices of the velocity modulation type, electrical tuning means which employ the variable dielectric constant characteristic of a rotating space charge. It is further contemplated to obtain a relatively wide range of electronic tuning by adjustably controlling the strength of the magnetic field, or by adjustably controlling the strength of the electric field or by simultaneously adjustably controlling both the magnetic and the electric field strengths to which the space charge is exposed.

Accordingly, it is a principal object of the present invention to provide electronic means for and a method of rendering the natural oscillation frequency of cavity-type resonators in velocity modulation electron discharge tube devices continuously variable and adjustable over a relatively wide range of frequencies.

Another object of the present invention is to provide a high frequency electron discharge tube structure, wherein a wide range of tuning is made available through the application of a rotating space charge maintained within the cavity resonator of said structure.

Still another object of the present invention is to provide a high frequency electron discharge tube device having electronic means for tuning said device, which means are substantially free of amplitude effects, thus rendering said tuning means especially useful in frequency modulation devices.

A feature of the present invention resides in the provision of an electron space charge in the cavity resonator of a velocity modulation type of electron discharge tube and means including a uniform magnetic field for rotating said space charge at a predetermined angular velocity,

whereby the effective dielectric constant of said resonator is varied, thus producing a corresponding variation in the natural frequency of oscillation of the resonator.

The invention in another of its aspects relates to novel features of the instrumentalities described herein for achieving the principal objects of the invention and to novel principles employed in those instrumentalities, whether or not these features and principles are used for the 10 said principal objects or in the said field.

A further object of the invention is to provide improved apparatus and instrumentalities embodying novel features and principles, adapted for use in other fields.

Other objects and advantages will become apparent from the specification, taken in connection with the accompanying drawings wherein preferred embodiments of the invention are illustrated.

In the drawings,

Fig. 1 is a longitudinal sectional view of a high frequency electron discharge tube embodying the invention;

Fig. 2 is a sectional view taken along the line 25 2-2 of Fig. 1; and

Fig. 3 is a fragmentary view of a modified form of the invention.

Referring particularly to Figs. 1 and 2, there is shown an electron discharge tube structure of the velocity modulation type commonly known as a Klystron. For the purpose of the present description only, and, without intending to be limited thereto, the present invention has been embodied in a reflex type of Klystron whose fundamental theory of operation is similar to that described with respect to Fig. 2 of United States Letters Patent No. 2,250,511, issued July 29, 1941, to Russell H. Varian and William W. Hansen, for "Oscillator Stabilization System." It will be understood, however, that the present invention is not limited to use in reflex Klystrons since it may be employed with equally satisfactory results in other types of velocity modulation devices such as any of the many forms of multiple resonator Klystron oscillators, amplifiers, frequency-multipliers, etc.

The improved reflex Klystron illustrated in Figs. 1 and 2 comprises a cylindrical evacuated resonator shell 11 having opposed rigid end walls 13 and 15 that are centrally apertured for the purpose of receiving and mounting thereat a tubular reentrant portion 17 and a tubular pedestal 19, respectively.

The reentrant portion 17 extends through the opening in wall 13 coaxially with shell 11 and is terminated within said shell 11 at a point closely spaced from wall 15 in a perforated grid structure 21 spaced from and parallel to a similar grid structure 23 mounted in the aperture of wall 15.

For providing a well-defined beam of electrons, there is mounted within the pedestal 19 a cathode structure comprising an indirectly heated cathode 25 having a filamentary heater 27 excited from a filament transformer 29 through a vacuum-sealed base structure 31. The primary winding of transformer 29 may be energized from any suitable current source (not shown). Cathode 25 is shown provided with a collimating shield 33 for collimating the electron beam to direct the same through the aligned grids 21, 23.

A reflector plate 35 is coaxially supported within the reentrant portion 17 by means of conducting rod 37 which, in turn, is vacuum-

sealed in insulation cap seal 39 provided at the outer end of reentrant portion 17. A difference of potential between cathode 25 and reflector 35 is maintained by a battery 41. If desired, the potential of the reflector 35 with respect to the cathode 25 may be made either positive or negative by means of a voltage-dividing variable tap arrangement shown at 43. A relatively high accelerating voltage from a high voltage source 45 is applied between the cathode 25 and grid 23 by connecting one terminal of the source 45 to the tube wall and the other terminal to the cathode lead, as shown. So connected, grid 23 serves as an anode for attracting electrons emitted from cathode 25.

As thus far described, the reflex Klystron herein disclosed is of conventional design and operation. The electron stream from the cathode initially traverses the gap between resonator 20 grids 21, 23 and is then returned by reflector 35 into the resonator 11 so as to excite and maintain an oscillatory electromagnetic field therein. Accepted theories of this action based on electron velocity modulation principles are explained fully in the above-mentioned Patent No. 2,250,511, to which reference is made for further details. Ultra-high frequency energy is extracted from the resonator field as by the usual concentric line terminal assembly 47.

To provide for an electronic space-charge or cloud within the resonator shell 11, an auxiliary indirectly heated cathode structure is provided comprising a heater coil 49 of insulated wire closely wound between walls 51, 53 of a double-walled metallic cylinder 55. A coating 57 of electron emitting material is suitably applied over the exterior surface of the outer wall 51 of the cylinder 55. The heater coil 49 and the cylinder 55 assembly is preferably mounted coaxially with the reentrant portion 17, as shown, to minimize distortion of the resonator field, being slightly spaced from the portion 17 and supported in position by a metallic tube 59 rigidly fastened to cylinder 55 around a suitable opening 35 therein. Tube 59, in addition to its supporting action, forms the inner conductor of a coaxial line terminal structure having an outer conductor 61 rigidly secured to or integral with the end wall 13 of shell 11. Wire 49 may conveniently be brought out of the resonator space and connected to one terminal of a heater battery 63 by running it up through the interior of tubular inner conductor 59. The other end of wire 49 may be spot welded to the double-walled cylinder 55 as at 65. The heater supply circuit for wire 49 is completed by connecting the other terminal of battery 63 to tubular inner conductor 59, as illustrated. Filter sections 67, 69 formed as quarter-wavelength lengths of coaxial transmission line are provided to isolate the heater current circuit from the high frequency energy contained within the resonator.

For attracting electrons emitted from the auxiliary cathode, an open-ended cylindrical auxiliary anode 71 is mounted radially spaced from and coaxially supported with respect to the auxiliary cathode supporting cylinder 55 by means of a rigid conducting rod 73, which, in combination with tubular outer conductor 75 secured to resonator 11, forms a coaxial line terminal structure having quarter-wavelength coaxial transmission line filter sections 77, 79 useful to inhibit leakage of high frequency energy from the resonator. 70 A positive potential is maintained on anode 71

relative to the auxiliary cathode by means of variable-voltage battery 81 which is connected to said anode 71 through the secondary winding of an input transformer 83 and the coaxial line filter sections 77, 79.

During the course of travel from cathode emitter surface 57 to anode 71, the electrons are forced to traverse spiral paths by an axial magnetic field produced by a coil 85 of which the windings are suitably connected to a variable energizing battery 87. To concentrate the magnetic field produced by the coil 85, a soft iron shell 89 is provided having poles as at 91 and 93. If desired, the electromagnet may be replaced by a permanent magnet with variable shunt, for the same purpose.

Fig. 3 shows a considerably simplified modification of the present invention. In place of the type of auxiliary cathode hereinabove described, a simplified cathode structure is provided comprising a coating 95 of electron emitting material applied directly to the outer surface of the reentrant portion 17 and a heater coil 97 is mounted interiorly and coaxially of said reentrant portion 17, the heater leads being brought out, as wires 99, through seal 39. If desired, a cylindrical jacket 100 may be mounted interiorly of said reentrant portion 17 and coil 97 to serve as a heat shield for directing the heat from coil 97 toward the coating 95. By this construction, the use of separate high frequency filter circuits 67, 69 (Fig. 1) for the auxiliary cathode and anode structures is obviated inasmuch as the space within reentrant portion 17 is free from high frequency fields.

Also, anode 71, shown in the embodiment of Figs. 1 and 2, may be eliminated as a separate structure within the resonator shell 11 and, in place thereof, the cylindrical wall of the resonator 11 may be employed, being insulated from the pole 17. Thus, a positive potential from variable voltage source 102 may be applied to the resonator side wall relative to the auxiliary cathode through a suitable radio frequency filter arrangement 101 for minimizing leakage of high frequency energy from the resonator. If desired, more elaborate filters such as quarter-wave sections can be used in place of filter 101. It will be observed, that, by using the simplified auxiliary cathode construction described above together with the resonator side wall as the anode, a rotating space charge may be provided without introducing any auxiliary electrodes into the resonator space.

It has been found that the presence of separate auxiliary cathode and anode structures of the type shown in Figs. 1 and 2, in the resonator reduces it Q by only an inconsequential amount, approximately 15-20%. This relatively low reduction in Q is, in a large measure, due to the fact that the auxiliary electrodes are placed so that metal surfaces thereof are approximately perpendicular to the high frequency field, as shown in Fig. 1, and that said electrodes are supported by the quarter wave filters 67, 69 and 77, 79. It will be understood that any number of such filter supports may be used as are mechanically desirable.

In operation, the electronically tuned tube in either of the herein disclosed modified forms is normally permitted to function in accordance with the mode and principles of operation set forth in the above-mentioned Patent No. 2,250,511. For obtaining a wide range of tuning, the voltage of battery 87 is varied, producing cor-

responding variations in the strength of the magnetic field and thereby varying the angular velocity of rotation of the space charge or cloud of electrons produced by the auxiliary electrodes.

5 The variations of angular velocity of the cloud produce corresponding alterations in the dielectric constant of the resonator space, thus changing the natural resonant frequency of the resonator and the oscillatory electromagnetic field associated therewith.

Frequency changes of the resonator are also obtainable by varying the strength of the radial electric field between the auxiliary cathode and anode as by varying the voltage of battery 81. It has been observed that, to obtain the widest possible tuning range, batteries 87 and 81 may both be varied together, in proper ratio.

For wide band frequency modulation, I propose to apply a signal voltage in series with the 20 battery 81 voltage by means of transformer 83, as shown. Alternatively, the frequency modulation signal voltage may be applied in series with battery 87 by means of transformer 103, or in both places simultaneously.

25 Since many changes could be made in the above construction and many apparently widely different embodiments of this invention could be made without departing from the scope thereof, it is intended that all matter contained in the 30 above description or shown in the accompanying drawings shall be interpreted as illustrative and not in a limiting sense.

What is claimed is:

1. Apparatus for generating electromagnetic energy adjustable over a wide range of ultrahigh frequencies, comprising electron-beam producing means comprising a cathode and means for focusing electrons emanating from said cathode into a beam of predetermined cross-section;
- 20 hollow conductive means adapted to contain a dielectric medium for sustaining an oscillating electromagnetic field at a resonant frequency of said medium to act on said beam of electrons, said conductive means comprising parallel, closely spaced perforate portions in the path of the electrons of said beam, a tubular reentrant portion extending from one of said perforate portions and surrounding the path of said beam and an annular wall portion extending from adjacent said 25 tubular portion to the other perforate portion defining an annular cavity adapted to sustain an oscillating electromagnetic field such that a substantial component of the electric field will appear between said perforate portions; a reflector electrode disposed in the path of the electron beam and spaced from said cathode beyond said perforate portions to reflect said electron beam after its passage through said perforate portions whereby said electron beam is enabled to excite the electromagnetic field within said dielectric medium, an annular second cathode coaxial with and at least partially surrounding said reentrant portion, anode means likewise coaxial with and at least partially surrounding said reentrant portion and radially spaced from said annular cathode for maintenance of a flow of electrons from said annular cathode toward said anode means, magnetic-field-producing means disposed adjacent said wall portion and adapted to produce a magnetic field relatively strong within and substantially parallel to the axis of the space between the annular cathode and said anode means, whereby electrons from the annular cathode are caused to move in spiral paths, and means cou- 30 plied to at least one of said magnetic-field-pro-

ducing means and said anode means for adjusting the relation between the strength of the magnetic field and the potential between said anode means and said annular cathode to vary the frequency of the electromagnetic field.

2. Ultra-high-frequency apparatus adjustable over a wide range of frequencies, comprising means for producing a beam of electrons, a cavity resonator having parallel, closely spaced, perforate portions disposed along the path of said beam, said resonator also having a tubular re-entrant portion extending from one of said perforate portions and surrounding said beam path and an outer wall portion connecting said tubular portion to the other of said perforate portions to define an annular cavity adapted to contain an electromagnetic field to interact with said beam, an annular cathode coaxial with and at least partially surrounding said reentrant portion, anode means likewise coaxial with and at least partially surrounding said reentrant portion and radially spaced from said cathode for maintenance of a flow of electrons from said annular cathode toward said anode means, magnetic-field-producing means disposed adjacent said outer wall portion and adapted to produce a magnetic field within said resonator and substantially parallel to the axis of said cathode and said anode means, and means coupling a potential source between said cathode and said anode means whereby electrons from said annular cathode are caused to move in spiral paths, and means coupled to at least one of said magnetic field producing means and said anode means for adjusting the relation between the strength of said magnetic field and the potential between anode and cathode, whereby the resonant frequency of the resonator may be varied.

3. In a velocity modulation tube for producing ultra-high frequency energy, conductive means defining a hollow cavity resonator enclosing a space in which an electrical field may resonate, said resonator including a pair of electron-permeable walls positioned in mutually spaced relation, means including a cathode substantially aligned with said electron-permeable walls for passing a beam of electrons therethrough, means for producing a second electric field including a second cathode for producing a second electron stream in the space in said resonator in which the first-mentioned electrical field may resonate, magnetic field-producing means for producing a magnetic field in said resonator having a direction substantially normal to the direction of said second electric field and substantially parallel to the direction of said first beam of electrons, and means coupled to at least one of said field-producing means for varying the strength thereof relative to the other whereby the frequency of the resonating electrical field in said resonator may be varied.

4. In a velocity modulation tube for producing ultra-high-frequency energy, conductive means defining a hollow cavity resonator enclosing a space in which an electrical field may resonate, said resonator including a pair of electron-permeable walls positioned in mutually spaced relation, means including a cathode substantially aligned with said electron-permeable walls for passing a beam of electrons therethrough, means for producing a second electric field including a second cathode disposed within the cavity resonator and adapted to produce a second electron stream in the space therewith, magnetic field-producing means for producing a magnetic field

in said resonator having a direction substantially normal to the direction of said second electric field and substantially parallel to the direction of said first beam of electrons, and means coupled to at least one of said field-producing means for varying the strength thereof relative to the other whereby the frequency of the resonating electrical field in said resonator may be varied.

5. In a velocity modulation tube for producing ultra-high-frequency energy, conductive means defining a hollow cavity resonator enclosing a space in which an electrical field may resonate, said resonator including a pair of electron-permeable walls positioned in mutually spaced relation, means including a cathode substantially aligned with said electron-permeable walls for passing a beam of electrons therethrough, means for producing a second electric field including a second cathode disposed within said cavity resonator and arranged in concentric relation to the beam of electrons produced by the first mentioned cathode, said second cathode being adapted to produce a second electron stream in the space within said resonator, magnetic field-producing means for producing a magnetic field in said resonator having a direction substantially normal to the direction of said second electric field and substantially parallel to the direction of said first beam of electrons, and means coupled to at least one of said field-producing means for varying the strength thereof relative to the other whereby the frequency of the resonating electrical field in said resonator may be varied.

6. In a velocity modulation tube for producing ultra-high-frequency energy, conductive means defining a hollow cavity resonator enclosing a space in which an electrical field may resonate, said resonator including a pair of electron-permeable walls positioned in mutually spaced relation, means including a cathode substantially aligned with said electron-permeable walls for passing a beam of electrons therethrough, means for producing a second electric field including a second cathode disposed within said cavity resonator and in concentric relation to the beam of electrons produced by the first mentioned cathode for producing a second electron stream substantially perpendicular to said first electron beam, magnetic field-producing means for producing a magnetic field in said resonator having a direction substantially paralleling the electron beam produced by the first mentioned cathode, and means coupled to at least one of said field-producing means for varying the strength thereof relative to the other whereby the frequency of the resonating electrical field in said resonator may be varied.

7. In a velocity modulation tube for producing ultra-high-frequency energy, conductive means defining a hollow cavity resonator enclosing a space in which an electrical field may resonate, said resonator including a pair of electron-permeable walls positioned in mutually spaced relation, means including a cathode substantially aligned with said electron-permeable walls for passing a beam of electrons therethrough, means for producing a second electric field including a second cathode of annular configuration disposed within said cavity resonator and in concentric relation to the electron beam produced by the first mentioned cathode, the direction of the electron stream produced by said second cathode being substantially perpendicular to the direction of said first beam of electrons, an annular anode disposed within said cavity resonator in spaced,

concentric relation to said second cathode, magnetic field-producing means for producing a magnetic field in said resonator having a direction substantially normal to the direction of the second electric field and substantially paralleling the electron beam produced by the first mentioned cathode, and means coupled to at least one of said field producing means for varying the strength thereof relative to the other whereby the frequency of the resonating electrical field in said resonator may be varied.

8. Ultra-high-frequency apparatus adjustable over a wide range of frequencies, comprising means for producing a beam of electrons, a cavity resonator having parallel, closely spaced, perforate portions disposed along the path of said beam, said resonator also having a tubular reentrant portion extending from one of said perforate portions and surrounding said beam path and an outer wall portion connecting said tubular portion to the other of said perforate portions to define an annular cavity adapted to contain an electromagnetic field to interact with said beam, an annular cathode coaxial with and at least partially surrounding said reentrant portion, anode means likewise coaxial with and at least partially surrounding said reentrant portion and radially spaced from said cathode for maintenance of a flow of electrons from said annular cathode toward said anode means, means disposed adjacent said resonator for producing a magnetic field within said resonator and substantially parallel to the axis of said cathode and said anode means, means coupling a potential source between said cathode and said anode means whereby electrons from said annular cathode are caused to move in spiral paths, and means coupled to at least one of said magnetic field producing means and said anode means for adjusting the relation between the strength of said magnetic field and the potential between anode and cathode, whereby the resonant frequency of the resonator may be varied.

9. Ultra-high-frequency apparatus adjustable over a wide range of frequencies, comprising means for producing a beam of electrons, a cavity

resonator having parallel, closely spaced, perforate portions disposed along the path of said beam, said resonator also having a tubular reentrant portion extending from one of said perforate portions and surrounding said beam path and an outer wall portion connecting said tubular portion to the other of said perforate portions to define an annular cavity adapted to contain an electromagnetic field to interact with said beam, a reflector electrode disposed adjacent said resonator and in the path of said beam on the side of said resonator opposite said electron beam producing means, an annular cathode coaxial with and at least partially surrounding said reentrant portion, anode means likewise coaxial with and at least partially surrounding said reentrant portion and radially spaced from said cathode for maintenance of a flow of electrons from said annular cathode toward said anode means, means disposed adjacent said resonator for producing a magnetic field within said resonator and substantially parallel to the axis of said cathode and said anode means, means coupling a potential source between said cathode and said anode means whereby electrons from said annular cathode are caused to move in spiral paths, and means coupled to at least one of said magnetic field producing means and said anode means for adjusting the relation between the strength of said magnetic field and the potential between anode and cathode, whereby the resonant frequency of the resonator may be varied.
